RADIO-FREQUENCY PHASE SHIFT NETWORK

George B. MacKimmie, Montreal, Quebec, Canada, assignor to Radio Corporation of America, a corporation of Delaware

Application June 29, 1948, Serial No. 35,895

6 Claims. (Cl. 178—44)

1

This invention relates to radio frequency transmission line networks, and more particularly to improvements in phase shifters and the like for radio frequency energy.

The principal object of the invention is to provide phase shifters in which the amount of phase shift can be varied without producing any amplitude variations.

Another object is to provide phase shifters whose input and output impedances are constant and therefore independent of the amount of phase shift introduced.

A further object is to provide phase shifters of the described type including reactance elements in the form of short circuited transmission lines, wherein the positions of the short circuiting elements in said line sections bear a simple linear relationship to the amount of phase shift produced.

It is a further object of this invention to provide phase shifters which fulfill the foregoing objects notwithstanding electrical or mechanical irregularities in the said reactance elements, and therefore are simpler and more economical to design and construct than prior art devices having the same purposes.

The invention will be described with reference to the accompanying drawing, wherein:

Figure 1 is a schematic circuit diagram of a variable phase shifter network embodying the instant invention and illustrating the principles thereof, and

Figure 2 is a schematic diagram of a preferred embodiment of the invention including coaxial transmission line elements.

Reference is made first to Figure 1, which shows four transmission line sections 1, 3, 5 and 7 connected serially in a closed loop to form a bridge-like circuit having four sets of terminals at the line junctions 9, 11, 13 and 15, respectively. Each of the line sections may have a length of one quarter, or an odd number of quarters, of the wavelength of the energy with which the device is to operate. Any one of the line sections, for example, the line 3, includes polarity reversing means such as a transposition 17. As an alternative, all of the lines except one may include such means.

A further transmission line section 19, provided with longitudinally adjustable short circuiting means such as a shorting bar 21, is connected to the junction 15 between the lines 5 and 1. Another line section 23, similar to the section 19 but one quarter wavelength longer, is connected to the junction 11 between the lines 1

and 3. The line section 23 is provided with shorting means 25 like that on the line 19. The junctions 9 and 13 are connected respectively to a source and a load (not shown).

In the operation of the device of Figure 1, the shorting means 21 and 25 are set at positions on the lines 19 and 23 such that the effective lengths of said lines differ by a quarter wavelength. Thus, if the distance from the junction 15 to the bar 21 is x , the distance from the junction 11 to the bar 25 is $x + \lambda/4$.

Assuming that the line sections 1, 3, 5 and 7 are all of the same characteristic impedance, incident energy applied to the junction 9 will divide equally between the lines 1 and 7, arriving in the same phase at the junctions 11 and 15. At these points the energy divides again, part going out the respective lines 23 and 21, and part going along the lines 3 and 5. Assuming the characteristic impedances of the lines 23 and 19 are equal, the currents flowing into the lines 3 and 5 will be equal.

Since the line 3 includes the transposition 17, the current and voltage at the end of the line 3 which is connected to the junction 13 will be equal and opposite to those at the corresponding end of the line 5 which is connected thereto. Thus, that part of the current which travels directly past the junctions 11 and 15 balances out at the junction 13, simply circulating around the loop and producing no output to the load.

The current flowing into the line 23 is reflected at the short circuit 25 and returns to the junction 11, arriving at that point with a phase delay of

$$4\pi\left(\frac{1}{4} + \frac{x}{\lambda}\right)$$

radians, referred to its original phase. Similarly, the current flowing into the line 19 is reflected and returns to the point 15 with a delay of

$$\frac{4\pi x}{\lambda}$$

radians. These two currents are equal, and each divides equally at the respective junctions 11 and 15. The currents flowing from the junctions 11 and 15 into the lines 1 and 7 arrive at the point 9 with a phase difference of

$$4\pi\left(\frac{1}{4} + \frac{x}{\lambda}\right) - \frac{4\pi x}{\lambda}$$

or π radians, i. e. they are 180 degrees out of phase and therefore cancel.

The reflected currents from the lines 23 and 19 which flow into the lines 3 and 5 arrive at the point 13 in phase with each other, owing to the reversal at the transposition 17. These currents combine to flow from the junction 13 to the load. Since no energy (except for losses in the line elements) is dissipated in the network, substantially all of the energy applied to the junction 9 flows out of the junction 13 to the load. The phase at the point 13 lags that at the point 9 by a constant π introduced by the lines 7 and 5, plus an amount

$$\frac{4\pi x}{\lambda}$$

introduced by the shorted line 19. The phase lag introduced by the path including the lines 1, 3 and 23 is 360 degrees greater and thus is the same.

It will be apparent that the phase difference between the input and the output to the described network may be varied at will by moving the shorting bars 21 and 25 together, and that the change in phase will be directly proportional to the distance the bars are moved. The amplitude of the output is determined only by that of the input as long as no substantial dissipation occurs in the lines 19 and 23, so that no variation in amplitude is introduced by changing the positions of the shorts 21 and 25.

Since a line terminated in an open circuit will reflect as well as one terminated in a short circuit, variable length open ended lines could be substituted for the shorted lines 19 and 23. At present, however, it appears preferable for mechanical reasons to use short-circuited lines.

A shorted line of length x in general exhibits, at a definite frequency, the characteristics of a pure reactance such as a capacitor or an inductor. Consequently, the line section 19 may be replaced wholly or in part by a lumped reactance element, providing the terminal portion of length x of the line 23 is similarly replaced. Thus, a variable capacitor can be connected to the junction 15, with a similar capacitor connected to the junction 11 through a quarter wave line. If the two capacitors are varied simultaneously in the same manner, the phase at the junction 13 will shift accordingly, without variation in amplitude.

The phase shift network is designed to match the impedance of the source and load devices as follows: Suppose the input and output impedances are to be Z_1 . The characteristic impedances of the lines 1, 3, 5 and 7 are made equal and their impedance is denoted Z_2 . The characteristic impedances of the line sections 19 and 23 are also equal and the impedance is denoted Z_3 . In order to match impedances to prevent reflections at the junctions 9 and 13, the following relationship must be satisfied:

$$Z_3 = \frac{Z_2^2}{2Z_1}$$

Thus, assuming Z_1 and Z_3 are each 50 ohms, Z_2 must be $\sqrt{2}$ times 50 ohms, or about 70 ohms.

The system of Figure 1 may be constructed of open wire transmission lines, hollow wave guides, single wires adjacent a conductive ground plane, or any other known wave transmission elements. However, it is preferred at present to use coaxial transmission line sections, as shown in Figure 2. The various coaxial line sections in Figure 2 correspond in length and in function to the similarly designated elements in Figure 1.

The transposition 17 of Figure 1 is replaced by a section 17' of line one half wavelength long. Since the delay in a half wavelength line section is π radians or 180 degrees, the effect of this section is simply to reverse the phase, exactly as a transposition would do. It should be noted incidentally that a transformer or other known phase reversing device may be substituted for the transposition 17 in Fig. 1 or the half wavelength line section 17' of Figure 2. In the illustrated embodiment, the total length of the line 3 and the additional section 17' is three quarters wavelength. The lines 1, 5, and 7 are each one quarter wavelength, as in Figure 1.

15 The ends of the lines 23 and 19 remote from the junctions 11 and 15 respectively are provided with slotted extensions 23' and 19' respectively which contain movable shorting plugs 25 and 21. The slots are provided for access to the plugs, which are mechanically ganged together as by a rod 29. Also connected to the shorting plugs is an indicator pointer 31, which moves over a scale 33 calibrated in degrees or other units of phase, to show the amount of phase shift being introduced by the network.

20 The operation of the system of Figure 2 is substantially identical with that of Figure 1. It will be apparent that the lines 23 and 19 can be made of any convenient length, as long as they differ by a quarter wavelength or an odd 25 number of quarter wavelengths. A point of considerable practical importance which should be noted is that the extensions 23' and 19' need not have the same characteristic impedance as the lines 23 and 19, as long as they are identical with each other. Thus, while at first glance the described structure appears to be more complicated than a simple variable length line or "trombone" for phase shifting, it is in fact much simpler to build because no impedance matching is required between the variable elements and the remainder of the system, and any irregularities in the variable-length line stubs will not change the input and output impedances, nor affect the amplitude of the output.

45 I claim as my invention:

1. A phase shifter for radio frequency oscillatory energy of a certain wavelength, comprising four transmission line sections connected serially 50 to form a closed loop and each having lengths which are integral odd numbers of quarters of said wavelength, one of said sections differing in effective length from the others of said sections by an amount equal to an odd integral number of half wavelengths, means applying said energy to two of said line sections at their junction, means providing output energy from the other two of said line sections at their junction, two reactance elements each coupled to one 55 of said first two line sections at its junction with the corresponding one of said second two line sections and the coupling between one of said reactance elements and the respective line section junction including a further line section having an effective length greater than the coupling of the other of said elements by an odd integral number of said quarter wavelengths.

60 2. The invention as set forth in claim 1, where- 70 in all of said transmission line sections are of equal effective lengths, and one of said sections includes means reversing the phase of energy travelling therethrough.

65 3. The invention as set forth in claim 1, where- 75 in three of said transmission line sections are

each one quarter wavelength long and the fourth of said line sections is three quarters wavelengths long.

4. The invention as set forth in claim 1, wherein said reactance elements are substantially identical. 5

5. The invention as set forth in claim 4, wherein said reactance elements comprise a pair of transmission line sections, each including movable short-circuiting means, and means mechanically coupling said short circuiting means together for gang operation.

6. The invention as set forth in claim 5, wherein the characteristic impedance Z_2 of said line sections connected to form said closed loop, 15 the characteristic impedance Z_3 of said line sections comprising said reactance elements, and the impedances Z_1 of said means applying energy

to and absorbing energy from said network are related as follows:

$$Z_3 = \frac{Z_1}{2Z_1}$$
